UNITED STATES PATENT OFFICE.

GEORGE W. ROBERTS, OF VICKSBURG, MISSISSIPPI.

PLANT-PROTECTOR.

1,145,266.

Specification of Letters Patent.

Patented July 6, 1915.

Application filed May 29, 1914. Serial No. 841,910.

To all whom it may concern:

Be it known that I, GEORGE W. ROBERTS, a citizen of the United States, residing at Vicksburg, in the county of Warren and 5 State of Mississippi, have invented new and useful Improvements in Plant-Protectors, of which the following is a specification.

This invention relates to plant protectors of that class comprising a hood or cover and 10 means whereby the same may be supported above a plant for the purpose of protecting the same against frost.

One object of the invention is to produce a simple and inexpensive conical protector 15 made of paper or cardboard and having a support formed with a reinforcing band.

A further object of the invention is to simplify and improve the construction of the conical hood and the supporting member 20 and the manner of assembling the same.

With these and other ends in view which will readily appear as the nature of the invention is better understood, the same consists in the improved construction and novel 25 arrangement and combination of parts which will be hereinafter fully described and particularly pointed out in the claim.

In the accompanying drawing has been 30 illustrated a simple and preferred form of the invention, it being, however, understood that no limitation is necessarily made to the precise structural details therein exhibited, but that changes, alterations and modifications within the scope of the claim may be 35 resorted to when desired.

In the drawing,—Figure 1 is a perspective view showing the improved plant protector applied in position for use. Fig. 2 is a perspective view showing the supporting member 40 detached. Fig. 3 is a horizontal sectional view taken on the line 3—3 in Fig. 1.

Corresponding parts in the several figures are denoted by like characters of reference.

A conical hood 15 made of paper, light 45 cardboard or other suitable material, has overlapping edges 16, 17 secured together by means of wire clips 18, which latter also serve to secure the cone on a supporting member consisting of a rod or wire 20, the 50 same being bent to form at the upper end thereof a loop 22' constituting a handle, and said rod being also bent intermediate its

ends to form an angularly disposed loop or ring 25, said ring being disposed to surround the conical hood some distance below the apex of said hood to reinforce the same. It will be seen that the loop or ring 25 is disposed angularly with respect to the body of the supporting member or wire 20 in such fashion that when the supporting member is applied to the conical hood, the ring 25 will lie in a plane substantially at right angles to the axis of said hood. Fastening members, such as clips 27, are also used to connect the ring 25 directly with the body of the hood.

The improved protector may be readily manipulated by the handle portion 22', and the lower end of the supporting member may be driven into the ground, being inserted at a suitable distance from the stalk of the plant that is to be protected, and the supporting member being inserted into the ground obliquely in an outward direction from the root of the plant which, therefore, 75 will not be liable to be injured. The protectors may be applied at signs of approaching frosty weather and may be quickly removed when desired.

Having thus described the invention, what 80 is claimed as new, is:—

A plant protector comprising a conical hood formed of sheet material and having overlapping edges, in combination with a supporting member mounted exteriorly on 85 said hood along the line of the overlapping portions, said supporting member consisting of a wire provided at its upper end with a ring constituting a handle and formed intermediate the ends thereof with an angularly disposed loop surrounding the hood below the apex thereof, fastening members 90 whereby the overlapped edges of the sheet material forming the hood are secured together and upon the supporting member, 95 and other fastening members connecting the ring with the material of the hood.

In testimony whereof I affix my signature in presence of two witnesses.

GEORGE W. ROBERTS.
